187,502

CASING FOR A PHOTOGRAPHIC PROJECTOR OR SIMILAR ARTICLE

Alan W. Duncan, Itasca, Ill., assignor to Sears, Roebuck
and Co., Chicago, Ill., a corporation of New York

Application September 8, 1959, Serial No. 57,479

Term of patent 14 years

(Cl. D61—1)

FIG. 1.

Des. 187,502

PAGE 2

Fig. 2.

FIG. 5.

FIG. 4.

FIG. 3.

Fig. 1 is a front perspective view of a casing for a photographic projector or similar article embodying my new design;

Fig. 2 is a rear perspective view of the same;

Fig. 3 is a top plan view thereof on a greatly reduced scale;

Fig. 4 is a bottom plan view thereof; and

Fig. 5 is a vertical sectional view taken substantially along the line 5—5 of Fig. 3.

I claim:

The ornamental design for a casing for a photographic projector or similar article, as shown.
